PUNCH NEEDLE

Gustav A. Carlson, Chicago, Ill., assignor to The
Boye Needle Company, Chicago, Ill., a corpora-
tion of Illinois

Application January 8, 1941, Serial No. 373,660

2 Claims. (Cl. 112—80)

This invention relates to a punch needle. Such a needle is used for carrying yarn and other threads through a foundation fabric for forming loops on the one side of the fabric. Afterward, if desired, the loops may be cut to permit the yarn to spread and form a nap.

An object of the present invention is to provide a punch needle which will greatly facilitate the threading of the needle. A further object is to provide a punch needle with means for retaining the yarn or thread within the needle during the shifting or drawing of the thread. A further object is to provide a punch needle with a handle supported and formed so as to facilitate the punching operation while at the same time facilitating re-threading. Another object is to provide a punch needle equipped with a cooperating stop or guard member which further facilitates the threading of the needle and the punching operation. Other specific objects and advantages will appear as the specification proceeds.

The invention is illustrated, in a preferred embodiment, by the accompanying drawing, in which—

Figure 1 is a perspective view of a punch needle embodying my invention; Fig. 2, a top plan view; and Fig. 3, a perspective view of the guard member detached from the punch needle.

The punch needle comprises a single hollow member 10 with the front portion thereof forming a tubular needle 11, the rear thereof forming a flat handle 12, and the central portion thereof providing a circular support 13 for the shifting of the stop or guard member 14.

The needle portion 11 is provided with a point 15 and with an eye 16 in the pointed portion. A slot 17 runs rearwardly from the eye or point portion of the needle and terminates in an upwardly-flared bell member 18. The upwardly-flared bell portion 18 serves an important function in preventing the yarn from working out of the slot 17 during the feeding of the yarn forwardly.

At the rear of the needle portion 11 is the barrel portion 13 through which the slot 17 also extends in alignment with the slot 17 of the needle portion 11. The barrel portion 13 receives the circular clamping ring 19 of the guard member 14 and permits it to be shifted thereon.

At the rear of the barrel portion 13, the hollow member is flattened to provide a flat handle portion 12. This portion is relatively narrow in width and at its top thin edge is provided with a series of adjustment openings 20. It will be

noted that the handle portion 12 is flattened in alignment with the needle portion 11, as shown more clearly in Fig. 2, thus causing one side of the punch needle to lie in a straight line throughout its entire length. On the other side, the portion 13 extends somewhat beyond the remaining portions. The flattening of the handle increases its height and the shoulders 21 thus formed serve as a stop for the sleeve member 19 in the rearward adjustment movement thereof.

The stop or guard member 14 is provided with a collar or sleeve 19 receiving the barrel portion 13 so as to slide thereon and it is provided with a longitudinal slot 22 aligned with the slot 17 which extends continuously from the rear of handle 12 through the barrel portion 13 and the needle portion 11. Thus there is an open or lateral slot for the entire length of the punch needle and through which yarn may be drawn into the interior of the punch needle.

The guard member 14 is provided with a rearwardly-extending spring finger 23 having a depending point adapted to be brought into engagement with any of the adjustment openings 20. The guard is also provided with a forwardly-extending member 24 having a V-shaped flange 25 extending partially around the needle portion 11. It will be noted that the flat finger 23 of the guard extends along the narrow edge of the flat handle 12 and is thus entirely out of the way when the handle 12 is grasped by the fingers.

In the operation of the device, yarn is fed through the eye of the needle point 15 and then drawn rearwardly within the slot 17. This movement of drawing the yarn rearwardly for a very short distance causes the yarn to be fed quickly into the interior of the punch needle so that threading is in this way accomplished in a moment of time. The guard member may be shifted readily along the barrel portion 13 and the finger 23 brought into engagement with the desired opening 20. The punching operation then follows the usual course, yarn being fed forwardly through the needle portion 11 and eye 16 in each step of the operation. To remove the yarn from the device, it is only necessary to draw the yarn through the slot 17 beginning at the rear of the device and extending forwardly through slot 17 to the point.

In the feeding forwardly of the yarn or thread during the punching operation, there is a tendency for the yarn to leave the needle portion through the slot 17. I have found that this tendency can be overcome and the yarn maintained regularly within the needle portion by providing

the bell 18 which extends upwardly in an arcuate shape at the rear of the restricted needle portion 11.

While in the foregoing description, I have set forth certain details and arrangements, it will be understood that such details and specific structures may be widely varied by those skilled in the art without departing from the invention herein set forth.

I claim:

1. In a device of the character set forth, a hollow member comprising a tubular needle portion equipped with a point having an eye, a central barrel portion, and a flat handle portion, the barrel portion merging at its rear into the handle portion, said member having a slot running from said point through said tubular needle portion, said central barrel portion and said flat handle portion to the rear end of the handle portion, a guard having a sleeve engaging said barrel portion and being provided with a slot aligned with said first-mentioned slot whereby thread may be drawn into the interior of said handle, barrel and needle portions through said slots, said flat handle portion providing a rear stop for limiting rearward movement of said sleeve, and an outwardly flared bell portion at the rear end of the needle portion guarding said slot in the needle portion, the outer edge of said bell portion being

in substantial alignment with the outer surface of said flat handle portion.

2. In a device of the character set forth, a hollow member providing a tubular needle portion equipped with a point and an eye therein, a central barrel portion, and a flat handle portion, the barrel portion merging at its rear into the handle portion, said flat handle portion having one of its relatively narrow edges provided with a plurality of spaced openings, a guard member carried by said hollow member in slidable relation thereon and having a relatively narrow finger extending along said narrow edge and equipped with a point adapted to engage one of said openings, said finger lying against said narrow edge and within the width thereof, said member having a slot running from said point through said needle, barrel and handle portions to the rear end of the handle portion and said guard being equipped with a slot aligned with said first-mentioned slot whereby thread may be drawn into the interior of said handle, barrel and needle portions through said slots, and an outwardly flared bell portion guarding said slot at the rear of said needle portion, the outer edge of said bell portion being in substantial alignment with the outer surface of the flattened handle portion.

GUSTAV A. CARLSON.
